UNITED STATES PATENT OFFICE.

JULIUS GOTTSCHALK, OF NEW YORK, N. Y.

FILLER-FORM FOR EMBROIDERY.

1,221,440.

Specification of Letters Patent.

Patented Apr. 3, 1917.

Application filed March 27, 1916. Serial No. 87,014.

To all whom it may concern:

Be it known that I, JULIUS GOTTSCHALK, a subject of the Emperor of Germany, residing at New York, in the county of Bronx and 5 State of New York, have invented certain new and useful Improvements in Filler-Forms for Embroidery; and I do declare the following to be a full, clear, and exact description of the invention, such as will enable others skilled in the art to which it 10 pertains to make and use the same.

This invention relates to filler forms for embroidery and more particularly to washable forms of this character, and to the process 15 of making them.

The principal object of the invention is to provide a device of this character so constructed which, while sufficiently rigid to retain its shape, is yet flexible enough to adapt 20 it to conform to the foundation on which it is mounted and to which it is adapted to be applied by embroidering thereover, and which when laundered will not shrink or 25 disintegrate but will retain its initial shape during the life of the article to which it is applied.

Another object is to provide an improved process of making forms of this character.

Still another object is to so construct 30 forms of this character that they may be interlockingly engaged to form monograms, and for other purposes.

With these and other objects in view, the invention resides in certain novel features of 35 construction, and the combination and arrangement of parts which will be herein-after more fully described and claimed.

In the accompanying drawings:—

Figure 1 is a perspective view of the composite sheet from which this filler form is 40 cut out, showing it in the process of manufacture and before it has been compressed and dried;

Fig. 2 is a front elevation of a filler form 45 in the shape of a capital letter;

Fig. 3 is a transverse section on an enlarged scale taken on the line 3—3 of Fig. 2; and

Fig. 4 is a front elevation of one of the 50 forms employed in constructing a monogram.

Fig. 5 is a front elevation of a monogram complete.

The filler form 1 constituting this invention is produced in the following manner, to wit, by first forming an outer layer or facing

2 of wool felt fabric impregnated with a suitable stiffening substance which imparts sufficient body to the fabric to adapt it to be readily handled without crumpling and which retains the wool fibers in catenated condition. This facing 2 so formed is then coated on its inner face with a thick layer 3 of book binder's or similar paste. A backing 4 of tough parchment paper is then applied to the rear paste-coated face of the facing layer 2 and these superposed layers are then placed between compression members in the form of boards (not shown), which will absorb any excess of paste and 70 sufficient pressure is applied thereto to cause the paste to penetrate the felt facing and securely unite it to the parchment paper backing. These layers remain in the press for about a week more or less which will be sufficient to compress the fibers of the felt fabric into compact form, to force the paste thereinto and to permit the paste to partially dry. The sheet S formed thereby is then removed from the press and the drying 80 thereof completed so that the firmly compressed fibers of felt will be held by the paste and all danger of shrinkage of the material when afterward subjected to moisture will be avoided. After the sheet S is 85 entirely dry the rear face of the backing 4 thereof is preferably coated with a suitable adhesive 5 which is designed for attaching the filler forms struck out from sheet S to the article to which they are to be applied. 90

After the adhesive coating 5 is dried, the sheet S is ready for the cutting out therefrom of the filler forms shown at 1. These forms 1, which may be of any desired configuration, are cut or stamped out from sheet S by suitable shaping and embossing dies (not shown) which impart to the forms the peculiar embossed effect shown in Fig. 3. 95

Much experimenting in constructing forms of this character has proven that in order to render them sufficiently rigid and to adapt them to retain their embossed shape, it is essential that the backing 4 of parchment paper or analogous material be employed. 100

After these forms have been so cut out they are ready for use and may be put up in packages ready for use or for sale. 105

In the use of these forms, one having the desired configuration is selected and is attached to the article to which it is to be applied, by moistening the gum or glue on the rear face thereof and cementing it in 110

position on the article on which it is to be mounted. After it has been so attached, it is secured in position by embroidering thereover in the usual manner, performing 5 the function of the ordinary filler used in embroidery of this character.

By constructing these filler forms in the manner above described they will retain their shape indefinitely and when the article 10 to which they are attached is laundried they will not disintegrate when thoroughly saturated with water or a cleansing fluid. The wetting operation will dissolve the paste and glue of the form but the wool fibers of 15 the felt will not shrink, and when the article is dried these fibers will expand and fluff out, thereby completely filling the casing formed by the embroidery threads and present a full padded appearance, the same as 20 before being laundried.

When it is desired to combine two or more of these forms to produce a monogram or for other purposes they are interlocking engaged by weaving them together, and when closed letters or forms 25 are used, such for instance as B, B, as shown in Fig. 5, the top and bottom cross bars 10 and 11 are slit transversely at diagonally opposite points as shown at 12 and 13 to 30 provide for the intertwining of the two letters, the top letter having the upper portion of one side bar 14 inserted through slit 12 in the upper cross bar 10 and its other side bar 15 positioned over and concealing 35 said slit 12 while the lower portion of its side bar 15 is passed through slit 13 and under the lower cross bar 11 of the lower letter and its side bar 14 disposed over and concealing said slit 13, as shown 40 in Fig. 5. It will thus be seen that the letters may be readily woven together and held in interlocking engagement by gluing the letters together at their points of intersection, it being only necessary to moisten the 45 gum or mucilage on the backs of the overlapping portions.

While this filler form is shown and described as a letter form, obviously it may be of any desired configuration.

I claim:—

1. A washable filler form comprising an outer facing layer of stiffened wool felt fabric, a parchment paper backing united to said layer, and an adhesive arranged on the outer face of said backing. 50 55

2. A washable filler form comprising an outer facing layer of stiffened wool felt fabric, a parchment paper backing having an adhesive on its outer face, and a thick layer of dissolvable paste arranged between 60 said facing and backing and compressed into uniting engagement with said facing and backing.

3. The process of making a washable filler form for embroidery which consists in first 65 forming a composite sheet by coating one face of a layer of wool felt with a thick layer of dissolvable paste, then superposing said paste coated felt layer on a flexible backing, then compressing the so disposed 70 layers until they are firmly united and the sheet formed thereby partially dried, then removing said sheet from compression and completing the drying thereof, and then cutting out forms of desired configuration 75 from said sheet.

4. The process of making a washable filler form for embroidery which consists in first forming a composite sheet by coating a 80 facing layer of stiffened wool felt with a thick layer of dissolvable paste, then superposing said stiffened paste coated felt layer on a parchment paper backing, then subjecting the so disposed layers to compression and an absorbing medium until the 85 layers are firmly united and the sheet formed thereby partially dried, then removing said sheet from compression and completing the drying thereof, and then cutting out forms of desired configuration from 90 said sheet.

In testimony whereof I have hereunto set my hand in presence of two subscribing witnesses.

JULIUS GOTTSCHALK.
